United States Patent Office.

JOEL G. GARRETSON AND OLIVER S. GARRETSON, OF BUFFALO, NEW YORK.

Letters Patent No. 96,908, dated November 16, 1869.

IMPROVEMENT IN SASH-HOLDER.

The Schedule referred to in these Letters Patent and making part of the same.

To all whom it may concern:

Be it known that we, JOEL G. GARRETSON and OLIVER S. GARRETSON, of Buffalo, in the county of Erie, and State of New York, have invented a certain new and useful Improvement in Sash-Locks; and we do hereby declare that the following is a full and exact description thereof, reference being had to the accompanying drawings, making part of this specification.

Figure 1 is a perspective view of the lock complete.

Figure 2, 3, 4, and 8, are different views of the case or frame of the lock.

Figures 5, 6, and 7, are different views of the bottom-plate.

Figures 9 and 10 are views of the eccentric.

Figures 11 and 12 are views of the cam-bolt.

Like letters of reference indicate corresponding parts in all of the figures.

Our improvements belong to that class in which the lock is applied to the sash of the window, and acts against the window-strip, to prevent the sash from being raised from the outside, and to prevent its falling when raised.

A sash-fastener, consisting of a bolt, which is pressed by an eccentric against the casing, so as to prevent the raising or lowering of the sash, is old, and such we do not broadly claim.

Our invention consists—

First, in so constructing and arranging the cam or eccentric with a slotted cam-headed bolt, that the pivot which secures the former shall pass through the slot in the latter, and form a common pivot or centre for both, so as to permit the head of the bolt to yield vertically, and cause the cam-surface thereof, in contact with the casing, to wedge against the latter, as the sash is attempted to be raised or lowered.

Second, in providing this slotted bolt with a lug at its outer end, with which the eccentric or cam-lever engages, and withdraws the bolt from contact with the casing in releasing the sash.

As represented in the drawings—

A is the case of the lock, recessed to receive the cam-bolt B and bottom-plate C.

It is also provided with a hole at its centre, for the rivet E to pass through, which holds all the parts of the lock together.

It is further provided with holes at its ends, for the reception of screws to fasten it to the sash of the window.

D is the eccentric, and pivots on rivet E, which passes through it a little out of centre, so that it revolves eccentrically to throw forward the bolt B.

It is also provided with a lever and thumb-piece, D, fig. 10.

The cam-bolt B is provided with a slot a, fig. 11, to allow it to move back and forth over rivet E.

It is provided, further, with a double cam-shaped head, with its periphery struck on a greater circle than if struck from any point within the slot a, fig. 11.

It is also provided with a projection, b, fig. 1, which engages with the periphery of the eccentric D, to draw the bolt away from the window-strip, so as to allow the sash to move freely.

The operation of our improved fastener will be readily understood.

When the eccentric D is revolved, its periphery presses against the head of bolt B, and moves it forward against the window-strip to support the sash.

The friction of the bolt against the window-strip tends to throw the head of the bolt in an opposite direction from that in which the sash is moving, and thus throws out a portion of the bolt-head that is further from the centre than the point at which it touched when thrown up by the eccentric, thus locking and holding the sash more firmly than it would do if the head of the bolt was a plain surface or was a segment struck from any point within the slot a of the bolt B.

By this arrangement we secure several important advantages:

First. The head of the bolt that bears against the window-strip is large and very slightly rounded, thus giving a large bearing against the window-strip, to prevent bruising or marring it, as is common with surface-locks.

Second. The lock is easily applied and operated, and has no spring or other delicate parts to get out of order.

Third. All the parts are simple of construction, and can be moulded and cast complete without drilling or other finishing, thus enabling it to be cheaply constructed.

What we claim as our invention, and desire to secure by Letters Patent, is—

1. The eccentric D, and the slotted and cam-headed bolt B, when so constructed and arranged that the pivot of the former shall pass through the slot in the latter, and form a common pivot for both, substantially in the manner set forth.

2. The lug b, at the outer end of the bolt B, arranged with the cam D, so that the latter in releasing the bolt shall engage with the lug, and withdraw the bolt from contact with the casing, as hereinbefore set forth.

In witness whereof, we have hereunto signed our names, in the presence of two subscribing witnesses.

J. G. GARRETSON.
